UNITED STATES PATENT OFFICE.

ARTHUR P. CONANT, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A WATCHCASE BOW.

Application filed October 9, 1925. Serial No. 15,077. Term of patent 14 years.

To all whom it may concern:

Be it known that I, ARTHUR P. CONANT, a citizen of the United States, residing at Fort Thomas, in the county of Campbell and State of Kentucky, have invented a new, original, and ornamental Design for Watchcase Bows, of which the following is a specification, reference being had to the accompanying drawing, forming part thereof.

Fig. 1 is a side view of the bow;

Fig. 2 is a cross section on a line 2—2 and Fig. 3 a cross section on the line 3—3 of Fig. 1; and

Fig. 4 is an isometric view of the bow partly broken away to show the shape.

I claim:

The ornamental design for a watchcase bow, substantially as shown.

ARTHUR P. CONANT.
